CLAIM

The ornamental design for housing for an automatic dialing telephone set or similar article, substantially as shown and described.

DESCRIPTION

FIG. 1 is a perspective view of housing for an automatic dialing telephone set or similar article showing our new design;

FIG. 2 is a second perspective view of the ornamental design;

FIG. 3 is a top plan view of the ornamental design of FIG. 1;

FIG. 4 is a front view thereof;

FIG. 5 is a rear view thereof;

FIG. 6 is a side view thereof; and

FIG. 7 is a fragmentary top plan view of a second embodiment of the design as shown in FIG. 1, the only difference being the inclusion of the grill.

The matter shown in broken lines in FIGS. 1, 2, 3 and 7 is for illustrative purposes only.
